(57) **CLAIM**

The ornamental design for a control panel and hub and the like, as shown and described.

DESCRIPTION

FIG. 1 is a perspective view of the control panel and hub of the present invention;

FIG. 2 is a perspective view of the control panel and hub shown in FIG. 1, illustrating a light thereof in an illuminated state;

FIG. 3 is a bottom view of the control panel and hub shown in FIG. 1;

FIG. 4 is a top view of the control panel and hub shown in FIG. 1;

FIG. 5 is a right side view of the control panel and hub shown in FIG. 1;

FIG. 6 is a left side view of the control panel and hub shown in FIG. 1; and,

FIG. 7 is a front view of the control panel and hub shown in FIG. 1.

The portions of the drawings shown in broken lines are for illustrative purposes only and form no part of the claimed design.

The radiating dashed lines in FIG. 2 illustrate a feature of the claimed design in an illuminated state.
